UNITED STATES PATENT OFFICE.

MILTON O. REEVES, OF COLUMBUS, INDIANA, ASSIGNOR, BY MESNE ASSIGNMENTS, TO THE HEIM GRINDER COMPANY, OF DANBURY, CONNECTICUT, A CORPORATION OF CONNECTICUT.

BALANCE GRINDING WHEEL.

Original application filed July 14, 1922, Serial No. 574,873. Divided and this application filed January 11, 1923. Serial No. 611,947.

To all whom it may concern:

Be it known that I, MILTON O. REEVES, a citizen of the United States, residing at Columbus, in the county of Bartholomew and State of Indiana, have invented a new and useful Balance Grinding Wheel, of which the following is a specification.

My invention relates to means for balancing or re-balancing grinding wheels.

10 One of the objects of my invention is to provide a support for the arbor of grinding wheels on which the arbor may be placed and the wheel be permitted to automatically roll until its heavy side is down, whereby 15 the unbalanced point of the wheel may be readily ascertained and proper balance given to the wheel.

20 My invention is particularly applicable for use in connection with the wheel balancing means shown in my co-pending application filed July 14, 1922, Serial No. 574,873, of which application this present application is a division.

25 For the purpose of disclosing my invention I have illustrated one embodiment thereof in the accompanying drawings in which,

30 Fig. 1 is a perspective view of the Reeves centerless grinder which is well known on the market, having my invention applied thereto;

35 Fig. 2 is a perspective view of a fragmentary portion of the base of said machine equipped with my invention and showing the grinder element in position to balance or re-balance;

40 Fig. 3 is a side elevation of one of the balancing ways of my invention designed as an attachment to existing grinding machines;

Fig. 4 is an end elevation thereof, and

Fig. 5 is a plan thereof.

45 As illustrated in the drawings the type of grinding machine with which my invention is shown as being associated includes a base 10 upon which is mounted a horizontally adjustable carriage 11 carrying the grinding wheel 12 which cooperates with the feed wheel 13 and work supporting bar 14 to 50 automatically rotate, axially advance, and grind articles placed in the grinding throat upon the bar 14. The feed wheel 13 is mounted to rotate upon a horizontal axis substantially at right angles to the axis of

the grinding wheel 12 and is carried by a 55 vertically adjustable carriage 15 mounted on suitable ways on the base 10. The above construction is well known on the market and is merely referred to here as typical of a grinding machine to which my invention 60 is particularly applicable for use.

The grinding and feed wheel elements of machines of this type are generally artificial compositions and for mounting the wheels are provided with an axial bore. A 65 sleeve extends through this bore being provided at one end with an annular flange 19 and at its opposite end with a splined collar arranged in opposition to the flange 19, the flange and collar being provided with 70 annular shoulders which fit within the central bore of the wheel 12. The wheel 12 is clamped firmly between the flange 19 and its cooperating collar by means of a nut threaded upon the end of the sleeve. This 75 sleeve is provided with a tapering axial bore which is adapted to receive the axially tapering hub of an arbor 33.

For balancing the wheels I preferably provide a plurality of balancing weights 80 which are arranged to be removably mounted in weight receiving openings or holes 35 on the flange 19 and clamping collar.

For receiving the arbor 33 and the wheel mounted thereon to permit the balancing of the wheel I provide a pair of runways or balancing ways 25, 25 which may be permanently incorporated in the machine or formed by separate brackets which may be attached to the machine. In any event I 90 prefer that the runways be closely associated with the grinding machine in order that the best results may be most conveniently obtained. In the structure illustrated each track or runway 25 is supported in an 95 accurate horizontal position by a bracket 26 provided at its upper corner with a horizontal cross foot 27 and a perforation adapted to receive a horizontal bolt 28 arranged to extend into the base of the machine 10. The foot 27 is so shaped as to form a fulcrum upon which the bracket may be rocked. At its lower corner the bracket is provided with a perforation 100 adapted to receive a bolt 29 and is so shaped as to normally stand some distance away from the machine base 10 so that a nut 30 may be threaded upon the bolt 29 105

between the base 10 and the bracket 26 so as to form an adjustable support for the lower end of the bracket, the bracket being clamped in desired position by a nut 31 on the bolt or stud 29 which extends from the machine base. The nut 32 on the bolt or stud 28 serves to clamp the foot 27 against the base 10.

By this arrangement each of the brackets 10 26 may be readily adjusted so as to bring its track 25 into a truly horizontal position whereby the pair of tracks will be level and will serve as a support upon which the balancing arbor 33 may roll.

15 The balancing of the wheel either initially, or subsequently to the period of wear, is accomplished by removing the wheel from the machine arbor and mounting the same on the balancing arbor 33 and placing 20 the arbor on the tracks 25 as indicated in Fig. 2. The wheel will of course automatically roll until its heavy side is down. The heavy side may then be compensated by the proper insertion of weights on the light 25 side. After weights have been inserted the wheel is again rolled on the tracks and if it again assumes the same light-heavy position the inserted weights may be adjusted or additional weights provided until the 30 wheel is properly balanced on the arbor. It will be seen that by the use of the tracks above described the unbalanced condition of the wheel may be readily observed and the tracks offer no obstruction to the manipulation of the balancing weights so that 35 after the wheel is once placed on the tracks the same need not be removed but may be properly balanced and tried. By the provision of the means whereby the tracks may 40 be adjusted, these tracks may be accurately leveled.

I claim as my invention:

1. A wheel balancing track support for grinding machines comprising a bracket 45 provided at one corner with a corner foot forming a fulcrum for the bracket and a horizontal perforation and a vertically spaced corner formed for engagement by a clamping means, and means to engage said 50 two corners to clamp the same in place and to adjust the bracket to levelism.

2. An attachment for grinding machines

comprising a bracket provided at one corner with a cross foot 27 and a perforation to receive a clamping bolt, a vertically spaced 55 corner with a perforated ear to receive another clamping bolt and a track 25 substantially as and for the purpose specified.

3. A balancing bracket member for application to a grinding machine comprising a 60 bracket of substantially triangular form having at one corner a transverse foot provided with a pair of spaced fulcra and an intermediate aperture, one side of the bracket adjacent said foot having a track 65 formed thereon and the other side adjacent the foot making an angle less than a right angle with the track side and terminating in a perforate ear portion, whereby said ear will normally stand a distance away 70 from the support for the bracket and provide a space to receive an adjustable clamp member, substantially as illustrated.

4. A wheel balancing track for attachment 75 to grinding machines including a track and a bracket for supporting said track, said bracket having a mounting member substantially at right angles to the track and arranged to be rockably secured at its upper end to a grinding wheel base and means at 80 the lower end of said mounting member for securing the same to the base and for adjusting said mounting member toward and away from the base to level the track.

5. A wheel balancing track for attachment 85 to grinding machines including a track and a bracket for supporting said track, said bracket having a mounting member extending substantially at right angles to the track and provided with a transversely extending brace to prevent lateral 90 rocking of the track, said mounting member having at its upper end means for rockably securing the same to a grinding wheel base and means at its lower end for securing 95 the same to the base and for adjusting the lower end toward and from the base for the purpose of leveling the track.

In witness whereof, I MILTON O. REEVES have hereunto set my hand at Columbus, 100 Indiana, this 8th day of January, A. D. one thousand nine hundred and twenty-three.

MILTON O. REEVES.
